(57) **CLAIM**

The ornamental design for a travel cap, as shown and described.

DESCRIPTION

FIG. 1 is a front, top and left side perspective view of a travel cap;
FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The features shown in broken lines within the opening in FIG. 7 illustrate portions of the travel cap that form no part of the claimed design.
